CLAIM

The ornamental design for an insect deterrent, as shown and described.

DESCRIPTION

FIG. 1 is a perspective view of an insect deterrent design showing my new design.

FIG. 2 is a front view of an insect deterrent.

FIG. 3 is a rear view of an insect deterrent.

FIG. 4 is a left side view of an insect deterrent.

FIG. 5 is a right side view of an insect deterrent.

FIG. 6 is a top view of an insect deterrent; and,

FIG. 7 is an enlarged view of an insect deterrent taken from the circle part in FIG. 2.

The broken lines in the drawings show portions of the insect deterrent that form no part of the claimed design. The long, single broken lines forming a circle around subject matter in FIG. 2 & FIG. 7 show the extent of the enlarged drawing view and form no part of the claimed design.
